UNITED STATES PATENT OFFICE.

ALFRED W. JANSEN, OF BROOKLYN, NEW YORK.

DESIGN FOR A CHIFFONNIER.

48,822.

Specification for Design.

Patented Apr. 4, 1916.

Application filed January 28, 1916. Serial No. 74,878. Term of patent 7 years.

To all whom it may concern:

Be it known that I, ALFRED W. JANSEN, a citizen of the United States, residing at Brooklyn, in the county of Kings and State of New York, have invented a new, original, and ornamental Design for a Chiffonnier, of which the following is a specification, reference being had to the accompanying drawing, forming part thereof.

The figure is a perspective view of a chiffonnier, showing my new design.

I claim:

The ornamental design for a chiffonnier as shown.

ALFRED W. JANSEN.

Witnesses:

CHRISTIAN H. ALMSTAEDT,
HAZEL V. REIDENBACH.
